MATRIX DRIER

Pearl Junius Hereford, Huntington, W. Va.

Application July 13, 1936, Serial No. 90,434

3 Claims. (Cl. 34—16)

This invention relates to improvements in matrix driers and has for its objects to provide a simply constructed oven which will evenly distribute the accumulated heat therein in a manner 5 to circulate around the green matrix and thoroughly dry the same evenly throughout its entire area.

These and other objects hereinafter set forth are accomplished by the means illustrated in the 10 accompanying drawings, in which

Fig. 1 is a perspective view of the improved oven;

Fig. 2 is a vertical sectional view taken longitudinally of the oven;

Fig. 3 is a horizontal sectional view taken on the line 3—3; and

Fig. 4 is a transverse sectional view taken on the line 4—4 of Fig. 2.

Similar reference numerals in all of the figures 20 of the drawings designate like parts.

This particular drying oven is formed with insulated side walls 10 all around, the walls preferably being constructed of sheet-metal having an insulating material enclosed between the same, 25 but it will be understood that I do not wish to be limited to the particular insulation set forth.

The top-wall is preferably a sheet of relatively thin metal 11 which is constructed to support a sheet of asbestos 12. A lid 13 hinged at 14, and 30 formed with depending flanges 15 is provided to cover the entire area of said top-wall, said lid being also provided on its underside with a sheet of foraminous material 16, such as wire-mesh or the like which is slightly spaced from the top- 35 wall of the lid. This top-wall of the lid is also provided with a plurality of apertures 17 adjacent its edges for a purpose hereinafter described.

The oven portion of the drier is formed by the 40 side-walls 10, top-plate 11, and a bottom-plate 18 preferably constructed of a double thickness of sheet-metal having supporting bars 19 which extend down at their ends and are suitably connected to the side-walls. The area of this supporting-plate is less than the cross-section of the oven; therefore, when supported centrally, heat 45 passages 20 are formed all around the edges of said plate.

Upon the upper surface of said bottom-plate 50 and suitably secured adjacent its edges are a plurality of grooved guides 21, one at each edge, which support the wire frame 22, formed with base-wires 23 that are adapted to rest in the grooves and arcuate end-frames 24. This wire-frame has secured thereto an arcuated wire-mesh

support 25 extending all around said arcuate end-frames 24, both together forming a supporting unit for the matrix to be dried. This supporting unit is removable from and replaceable in the oven by sliding the same in guides 21, and a door 5 26 is provided in the front wall of the oven to permit withdrawal or insertion of the supporting unit, with or without a matrix thereon.

Adjacent the top edges of the front and rear walls, the front wall being formed by the door 26 10 in this instance, suitable apertures 27 are provided for a purpose hereinafter stated.

An arcuated deflector 28 is secured to the underside of the top-wall 11 and side-walls and located to follow the contour of the arcuate mesh 15 of the matrix supporting frame and a sufficient distance therefrom to form a heat-chamber around the outside of the supporting frame. This deflector 28 is formed with a V-shaped groove at its top-side to form a heat baffle 28' at the top- 20 side of the oven.

Heat forming burners 29 of any suitable kind or construction, such as gas burners, oil burners or electric burners, are suspended in any suitable manner in the combustion chamber 30. In the 25 present instance, gas burners are shown.

In operation, the door 26 is opened and the matrix supporting frame is withdrawn from the oven and a wet matrix from the mold is placed upon the supporting frame mesh cover. The 30 supporting frame with the matrix thereon is then replaced in the oven and the door 26 is closed. The heat from the burners heats the bottom-plate 18 to transmit the heat therefrom to the underside of the supporting mesh 25 and the un- 35 derside of the matrix supported thereon. The heat from the burners also is deflected by the bottom-plate and passes through the edge passages 29 into the arcuate heat chamber formed by the deflector 28 and to the top-side of the matrix. 40 As the matrix dries, the moisture therein is driven out and escapes to the atmosphere through the apertures 27. It will be understood that the mesh support for the matrix is shaped to conform to the exact size of the matrix, so that it will be 45 evenly supported throughout its area while being dried. It will be further understood that when the heat from the burners rises through the heat passage 20, it is deflected against passing to the other side of the oven by the baffle 28', thereby 50 accumulating heat within the heat chambers at each side of the baffle and thus making an even temperature for drying the matrix.

The oven can be provided with legs or not as 55 desired.

It is obvious that a flat matrix can be dried by pressing the same between the foraminous sheet 16 and the asbestos filling 12 forming a part of the top-wall of the oven.

- 5 1. I claim:
1. A device of the character described, comprising an oven having a heatable bottom, a foraminous matrix support mounted slidably on said bottom, burners located beneath said bottom for 10 heating the same, heat passages around the edges of the bottom to permit heat to rise to the top-side of said foraminous support, apertures in the walls of the oven, and an arcuate heat deflector mounted in the oven in parallel relation to said 15 foraminous support to concentrate the heat to a matrix supported on its support, said arcuate deflector being formed with a baffle at its top-side to prevent circulation of the heat from one side of the oven to the other side.
  2. A device of the character described, comprising an oven having a heatable bottom, a foraminous matrix support formed of a single layer of wire mesh mounted slidably in suitable guides on said bottom, burners located beneath said bottom for 20 heating the same, heat passages around the edges of the bottom to permit heat to rise to the top-side of said foraminous support, apertures in the walls of the oven, and an arcuate heat deflector mounted in the oven in parallel relation to said foraminous support to concentrate the heat to a matrix supported on its support.

tom for heating the same, heat passages around the edges of the bottom at both sides of the oven to permit heat to rise to the top-side of foraminous support, apertures in the walls of the oven, and an arcuate heat deflector mounted in the oven in parallel relation to said foraminous support to concentrate the heat to a matrix supported on its support.

3. A device of the character described, comprising an oven having a heatable bottom, a foraminous matrix support mounted slidably on said bottom, said matrix support embodying a rigid wire frame for supporting the foraminous support, burners located beneath said bottom for heating the same, heat passages around the edges of the bottom at both sides of the oven to permit heat to rise to the top-side of said foraminous support, apertures in the outside walls of the oven, and an arcuate heat deflector mounted in the oven in parallel relation to said foraminous support to concentrate the heat to a matrix supported on its support.
